[57] **CLAIM**

The ornamental design for a housing for a multivariable transmitter, as shown and described.

DESCRIPTION

FIG. 1 is a front elevational view of a housing for a multivariable transmitter embodying our new design;

FIG. 2 is a right side elevational view thereof;

FIG. 3 is a top plan view thereof;

FIG. 4 is a rear elevational view thereof;

FIG. 5 is a left side elevational view thereof; and,

FIG. 6 is a bottom plan view thereof.

The broken line showing of end caps and couplings are for illustrative purposes only and forms no part of the claimed invention.
